US0D1074592S

(12) **United States Design Patent** (10) **Patent No.:** **US D1,074,592 S**
(45) **Date of Patent:** **** May 13, 2025**

(54) **CHARGER**

(71) Applicant: **Yingdan Ma**, Guangdong (CN)

(72) Inventor: **Yingdan Ma**, Guangdong (CN)

(**) Term: **15 Years**

(21) Appl. No.: **29/982,194**

(22) Filed: **Jan. 6, 2025**

(51) LOC (15) Cl. **13-02**

(52) U.S. Cl.

USPC **D13/108**
